UNITED STATES PATENT OFFICE.

NATHAN SHURE, OF CHICAGO, ILLINOIS.

DESIGN FOR A CANE-BADGE.

No. 38,131.

Specification for Design.

Patented July 24, 1906.

Application filed May 7, 1906. Serial No. 315,693. Term of patent 8½ years.

To all whom it may concern:

Be it known that I, NATHAN SHURE, a citizen of the United States, residing at Chicago, in county of Cook and State of Illinois, have invented a new, original, and ornamental Design for a Cane-Badge, of which the following is a specification, reference being had to the accompanying drawing, forming part thereof.

The figure in the drawing is a front elevation of a cane-badge embodying the design.

I claim—

The ornamental design for a cane-badge as shown.

NATHAN SHURE.
